Sidney Sanders,

JOHN CRANDELL AND P. W. SMITH, OF CHICOPEE, MASSACHUSETTS.

Letters Patent No. 92,428, dated July 13, 1869.

IMPROVED CURTAIN-FIXTURE.

The Schedule referred to in these Letters Patent and making part of the same.

To all whom it may concern:

Be it known that we, JOHN CRANDELL and P. W. SMITH, both of Chicopee, in the county of Hampden, and State of Massachusetts, have made and invented a new and useful Improvement in Curtain-Fixtures; and we do hereby declare that the following is a full, clear, and exact description of the construction and operation of the same, reference being had to the annexed drawings, making a part of this specification, in which like letters mark like parts, and whereof—

Figure 1 is a front elevation;

Figure 2, a side or edge elevation of the same; and Figure 3, a window showing the fixture attached.

Our invention relates to a brace or fixture for holding curtains, arranged on ordinary rollers, at any desired point of suspension.

To enable others skilled in the art to practise our invention, we describe the same as follows:

To the casing *a* we attach our invention, the brace *b*, and through the opening therein, *c*, we arrange the operating-cord *d*.

The opening *c* we make broad at one end, and gradually contract the same to a point, or nearly so, at the other.

When curtain *e* is raised to the desired height, cord

d is drawn forward into the narrow part of opening *c*, and there tightly clasped, holding the curtain suspended.

By pushing cord *d* back into the broad part of opening *c*, the curtain is released, and may be raised or dropped at pleasure.

The opening *c* may be cut quite out at one side of brace *b*, as indicated at *e*, fig. 1, for the more convenient arrangement of cord *d*, when provided with a tassel, and attached to roller *f*.

Thus having described our invention, let it be understood that we do not claim the combination of a knotted cord and staple, as in patent No. 63,169; but

What we do claim, and desire to secure by Letters Patent, is—

As a new article of manufacture, the brace *b*, constructed as herein described, and for the purpose specified.

JOHN CRANDELL.
P. W. SMITH.
